US007828672B2

(12) **United States Patent**
Billings

(10) **Patent No.:** **US 7,828,672 B2**
(45) **Date of Patent:** ***Nov. 9, 2010**

(54) **BALL FLIGHT ADJUSTMENT APPARATUS
FOR A GOLF CLUB HEAD**

(75) Inventor: **David P. Billings**, McKinney, TX (US)

(73) Assignee: **Dogleg Right Corporation**, Dallas, TX (US)

(*) Notice: Subject to any disclaimer, the term of this patent is extended or adjusted under 35 U.S.C. 154(b) by 0 days.

This patent is subject to a terminal disclaimer.

(21) Appl. No.: **11/467,142**

(22) Filed: **Aug. 24, 2006**

(65) **Prior Publication Data**

US 2006/0287129 A1 Dec. 21, 2006

Related U.S. Application Data

(63) Continuation of application No. 11/313,137, filed on Dec. 20, 2005, now Pat. No. 7,189,169, which is a continuation of application No. 10/043,421, filed on Jan. 10, 2002, now Pat. No. 7,004,852.

(57) **ABSTRACT**

A metal golf club head that allows a user to customize the location of the center of gravity. The metal golf club head comprises a hollow body with a weighting port. The weighting port allows a user to place weighting material inside the hollow body, customizing the location of the center of gravity, the swing weight, the total weight, and the balance of the golf club.

FIG. 3

FIG. 4

FIG. 5

FIG. 6

*FIG. 7**FIG. 8*## BALL FLIGHT ADJUSTMENT APPARATUS FOR A GOLF CLUB HEAD

CROSS-REFERENCE TO RELATED APPLICATIONS

This application is a continuation of, and claims the benefit of the filing date of, U.S. patent application Ser. No. 11/313,137 entitled CUSTOMIZABLE CENTER-OF-GRAVITY GOLF CLUB HEAD, filed Dec. 20, 2005 now U.S. Pat. No. 7,189,169, which is a continuation of U.S. patent application Ser. No. 10/043,421 entitled CUSTOMIZABLE CENTER-OF-GRAVITY GOLF CLUB HEAD, filed Jan. 10, 2002, now U.S. Pat. No. 7,004,852.

BACKGROUND OF THE INVENTION

1. Field of the Invention

The invention relates generally to golf clubs and, more particularly, to a golf club head in which the center of gravity, balance, and weight are customizable and can be altered to suit changing course conditions, weather conditions, and/or other user requirements.

2. Description of Related Art

Golfers have long recognized that they could alter the weight, balance, and performance characteristics by selectively adding weight to club heads. Typically, weight is added by applying thin strips of lead tape with an adhesive backing to the club head. In this manner the swing weight is increased and the center of gravity (CG) is altered to change the dynamics of the head during the swing and, therefore, the ball flight characteristics after contact. The location of the lead tape, however, is generally limited to the back, crown, and/or sole of the club heads where it would best stay affixed and not alter the look of the club, but this limits the adjustability options available to the golfer. For example, the lead tape could not be put on the face of the club to move the CG closer to the front of the club which is more desirable to some golfers who want the club to be easier to "work", i.e., to shape shots both in a left-to-right manner and in a right-to-left manner.

Furthermore, this use of lead tape was generally an additive process whereby the swing weight and total weight of the club was increased, often times negatively effecting other performance characteristics of the club. Some golfers overcame this obstacle by grinding down or using other means to reduce the weight of the club. However, this often damaged the protective finish of the club or the shape and configuration intended by the club designer, negatively effected the after market value of the club, and was difficult and time consuming for the golfer to adjust.

Furthermore, manufacturers of golf clubs have encountered problems when attempting to manufacture individual clubs to identical specifications because of variances of the individual components themselves and when assembled together. Generally, manufacturers build clubs to a weight at, or slightly below, a targeted weight specification and then add additional weight in the head and/or the shaft to increase the total weight and/or the swing weight to the desired specification. Additional weight is commonly added by pouring lead powder into the bottom of the shaft and sealing the shaft with a cork or other means. Alternatively, lead powder has been mixed with putty, epoxy, or other materials that are inserted into the end of the shaft of the assembled head and shaft to facilitate this final weight adjustment by the manufacturer. This method, however, alters the CG of the club away from the optimal location, adversely effecting performance and feel.

Additionally, a common practice has been to inject a hot melt glue or similar material into a hole in the club head during final assembly to arrive at a prescribed swing weight. The location that the glue puddles and adheres to the inner walls is determined by the orientation of the head while the glue is still hot and fluid. Furthermore, this technique has been used to customize the center of gravity of the club head for specific golfers' needs. The location of the glue, however, is generally limited to one broad area due to the closed process, and once the glue is set, the glue is not adjustable.

Several methods have been attempted to create a golf club that allows the weight, balance, and CG of golf club heads to be altered. One example is disclosed in U.S. Pat. No. 6,254,494 to Hasebe, et al. (hereinafter "Hasebe"), entitled, "Golf club head". The weights, which effect CG location and club head dynamics during the swing and the ball flight after contact, can be changed during manufacturing. Once manufactured, however, the weights can not be altered or be customized for individual needs. Therefore, a club head must be manufactured for each desired weighting configuration.

Another example is disclosed in U.S. Pat. No. 6,248,025 to Murphy, et al. (hereinafter "Murphy"), entitled, "Composite golf club head and method of manufacturing". Murphy discloses a weight strip within a ribbon of the body of the club head. Weights in the form of densified loaded films and/or ribbons of material denser than the primary composite material of the head are added to the internal structure to assertedly increase the forgiveness and playability characteristics, including the energy transfer. Murphy discloses that the location and configuration of the weights can be changed during manufacture to achieve varying characteristics, but, once the weights are added and the club head is completed in manufacturing, the weights can not be altered.

Yet another example is disclosed in U.S. Pat. No. 6,206,790 by Kubica, et al. (hereinafter "Kubica"), entitled "Iron type golf club head with weight adjustment member". Kubica assertedly discloses a weight adjustment member located within a secondary cavity within the back of a cavity back iron golf club head. The weight adjustment member is said to be chosen from a plurality of weight adjustment members to overcome variances in manufacturing tolerances and to adjust golf club swing weights to custom fit various golfers' requirements. The weight adjustment member, however, does not allow the position of the CG to be altered.

Yet still another example is disclosed in U.S. Pat. No. 3,652,094, to Glover (hereinafter "Glover"), entitled, "Golf club with adjustable weighting plugs". Glover assertedly discloses the use of threaded weight plugs to alter the CG. The location of the CG in Glover, however, is limited to the position of the threaded cavities. Similarly, U.S. Pat. No. 5,050,879 to Sun, et al. (hereinafter "Sun"), entitled, "Golf driver with variable weighting for changing center of gravity", assertedly discloses three cavities that are sealed by a cover plate in the sole where weight members can be selectively installed. However, the user's options for the location of the weight members is limited to adjustment between the three predetermined cavities, in the horizontal plane from heel to toe, and near the sole only.

Yet still another example is disclosed in U.S. Pat. No. 6,306,048 to McCabe, et al. (hereinafter "McCabe"), entitled, "Golf club with weight adjustment". McCabe assertedly discloses one or more weight chambers that the golfer uses to adjust the weight and CG of a club to customize it to his or her own needs. A filler material is used to set the weights in position. This method, however, limits the weights and weight changes to the location of the internal weight chamber,

and, once the filler material is set, the golfer can no longer adjust the weight or center of gravity.

Therefore, there is a need for a golf club head with a customizable CG that allows the CG to be altered by a golfer and/or the manufacturer.

SUMMARY

The present invention provides a metal golf club head that allows a user to customize the location of the center of gravity. The metal golf club head comprises hollow-body golf club head with a weighting port that allows the user to access the interior of the hollow-body golf club head. The weighting port allows a user to place weighting material, such as lead tape and the like, inside the golf club head, thereby customizing the location of the center of gravity.

BRIEF DESCRIPTION OF THE DRAWINGS

For a more complete understanding of the present invention, and the advantages thereof, reference is now made to the following description taken in conjunction with the accompanying drawings, in which:

FIG. 1 illustrates a metal golf club head that embodies features of the present invention;

FIG. 2 illustrates a bottom view of a metal golf club head that embodies features of the present invention;

FIG. 3 illustrates a rear view of a metal golf club head with a weighting port cover removed that embodies features of the present invention;

FIG. 4 illustrates a cross-section view with the weighting port cover attached that embodies features of the present invention;

FIG. 5 illustrates a metal golf club head with the crown portion removed to indicate some positions of weighting material;

FIG. 6 illustrates a metal driver head embodying features of the present invention;

FIG. 7 illustrates a metal iron golf club head embodying features of the present invention; and

FIG. 8 illustrates a metal putter head embodying features of the present invention.

DETAILED DESCRIPTION

Referring to FIG. 1 of the drawings, the reference numeral 100 generally designates a hollow golf club head embodying features of the present invention. The hollow golf club head 100 generally comprises a face portion 110, an integrated sole and wall portion 112, and a crown portion 114 defining a body 116 with an interior cavity 118. A hosel portion 124 is connected to and/or integrated into the body 116 for receiving a shaft (not shown). Furthermore, a removable, port cover 120, which is described in further detail below with reference to FIG. 3, provides access to the interior cavity 118, thereby allowing the placement of weighting material, such as lead tape, into the interior cavity 118.

In the preferred embodiment, the hollow golf club head 100 comprises a two-piece golf club head. The first piece comprising the integrated sole and wall portion 112 and the face portion 110, including the hosel portion 124. The second piece comprises the crown portion 114, which is welded or otherwise attached to the first piece. Other embodiments, such as a three-piece golf club head, however, may be used as is known in the art.

FIG. 2 is a bottom view of the hollow golf club head 100, further illustrating the positioning and sizing of the weight-

ing-port cover 120 in the preferred embodiment. Preferably, the weighting-port cover 120 is positioned on the bottom, i.e., the sole, of the hollow golf club head 100 and away from the face portion 110. Therefore, the weighting-port cover 120 is preferably positioned such that the weighting-port cover 120 is not visible by a golfer when addressing a golf ball. Furthermore, the placement of the weighting-port cover 120 away from the face portion 110 allows placement of weighting material about, or on, the interior side of the face portion 110, and along the heel/toe portions of the hollow golf club head 100, as will be described in greater detail below with reference to FIG. 4.

The weighting port cover 120 is preferably attached to the body 116 via a plurality of flush-mounted bolts 122, and, optionally, may be coated with a friction-reducing material, such as Teflon. In order to reduce the friction, the possibility of the weighting-port cover to "snag" onto grass, thereby affecting the swing path, and the wear and tear, the weighting-port cover 120 is flush-mounted to the integrated sole and wall portion 112 by the plurality of flush-mounted bolts 122.

FIG. 3 illustrates the hollow golf club head 100 with the weighting-port cover 120 removed. The body 116 preferably includes a recessed portion 310 configured for receiving an optional vibration-dampening ring 312 and the weighting-port cover 120. The vibration-dampening ring 312, such as a ring made from foam, rubber, and/or the like, allows the weighting-port cover 120 to be securely fastened, preventing a vibration/rattling noise that may occur as a result of swinging the club and/or striking a ball and sealing the interior cavity from exposure to outside elements, such as sand, water, and/or the like.

The plurality of flush-mounted bolts 122 pass through the weighting-port cover 120 and screw into the recessed portion 310 of the body 116. Alternatively, other methods, such as a weighting-port cover that screws into the body 116, latches, press fits, or the like, may be used. The preferred embodiment, however, allows for weighting-port cover 120 that is curved to match the contour of the body.

FIG. 4 illustrates a side view of the weighting-port cover 120 attached to the body 116 in accordance with the one embodiment of the present invention depicted in FIG. 3. As one skilled in the art will appreciate, the recessed portion 310 allows a smooth contour to be formed by the integrated sole and wall portion 112 and the weighting-port cover 120 when assembled. In an alternative embodiment, however, the weighting-port cover 120 is recessed from the integrated sole and wall portion.

FIG. 5 illustrates the hollow golf club head 100 with the crown portion 114 separated from the integrated sole and wall portion 112 in order to illustrate potential placements of weighting material in accordance with embodiments of the present invention. The illustrated positions are presented for illustrative purposes only and, therefore, should not limit the present invention in any manner. Furthermore, the positions may be used individually or in combination to further customize the location of the center of gravity. In the illustrated positions, the weighting material may be placed flush against and substantially parallel to a side of the golf club head 100.

Weight location 510 illustrates a low-front-center location, which is located on the integrated sole and wall portion 112 adjacent to the face portion 110, that imparts less spin on the ball and a high trajectory, resulting in easier workability (the ability to hit the ball from left to right and vice versa) and more carry (the distance the ball travels in the air).

Weight location 512 illustrates a high-front-center location, which is located on the crown portion 114 adjacent to the

face portion, that imparts less spin on the ball and a low trajectory, resulting in easier workability, less carry, and more rolling.

Weight location 514 illustrates a low-back-center location, which is located on the back-center of the integrated sole and wall portion 112, that results in more forgiveness and a high trajectory.

Weight location 516 illustrates a high-back-center location, which is located on the back-center of the crown portion 114, that results in more forgiveness and a low trajectory.

Weight location 518 illustrates a low-back-toe location, which is located on the back-center of the integrated sole and wall portion 112 along the toe, that results in more forgiveness and a high, fading trajectory.

Weight location 520 illustrates a high-back-toe location, which is located on the back-center of the crown portion 114 along the toe, that results in more forgiveness and a low, fading trajectory.

Weight location 522 illustrates a low-back-heel location, which is located on the back-center of the integrated sole and wall portion 112 along the heel, that results in more forgiveness and a high, drawing trajectory.

Weight location 524 illustrates a high-back-heel location, which is located on the back-center of the crown portion 114 along the heel, that results in more forgiveness and a low, drawing trajectory.

Weight location 526 illustrates a forward-center-center location, which is located on the center of the face portion 110, that results in easier workability with a neutral trajectory.

Weight location 528 illustrates a back-center-center location, which is located in the vertical-center of the integrated sole and wall portion 112, that results in neutrally forgiving club head.

Weight location 530 illustrates a low-center-center location, which is located on the center of the integrated sole and wall portion 112, that results in a neutral side-spin with a high trajectory. Note that this location is located on the weighting-port cover 120 for illustrative purposes only. As stated above, the weighting-port cover 120 may be located at any desired location, and a weight may be placed on the weighting-port cover 120 if so desired.

Weight location 532 illustrates a high-center-center location, which is located in the center of the crown portion 114, that results in a neutral side-spin with a low trajectory.

As shown in FIG. 5, the length of the weighting material may be oriented at various angles. As shown by weight locations 510, 512, 514, 516, 526, 528, 530, and 532, the length of the weighting material may be perpendicular to the vertical center plane of the golf club head 100. As shown by weight locations 518, 520, 522, and 524, the length of the weighting material may also be at other angles relative to the center plane. At angles such as the angles in weight locations 518, 520, 522, and 524, an axis along the length of the weighting material may intersect the vertical center plane of the golf club head 100 to form an acute angle.

As shown by weight locations 520 and 524 and weight locations 518 and 522, weighting material may be located at two locations substantially symmetrically on opposite sides of the vertical center plane of the golf club head 100. Axes along the length of the weighting material at each location may each intersect the vertical center plane of the golf club head 100 and form substantially equal angles.

As shown FIG. 5, an axis along the length of the weighting material at one location, such as weight location 520, may not be parallel to an axis along the length of the weighting material at another location, such as weight location 524. Further, as shown by weight locations 520 and 524 and weight loca-

tions 518 and 522, an axis along the length of the weighting material at one location may intersect an axis along the length of the weighting material at another location to define an angle whose vertex lies outside of the club body.

FIG. 6 illustrates a driver golf club head embodying features of the present invention in which the weighting-port cover 120 is located on the crown portion 114.

FIG. 7 illustrates a hollow, iron golf club head embodying features of the present invention in which a weighting-port cover 710 is provided.

FIG. 8 illustrates a hollow, putter golf club head embodying features of the present invention in which a weighting-port cover 810 is provided.

It should be noted that the placement and size of the weighting port is shown for illustrative purposes only, and, therefore, should not limit the present invention in any manner.

It is understood that the present invention can take many forms and embodiments. Accordingly, several variations may be made in the foregoing without departing from the spirit or the scope of the invention. For example, the weighting port may be of a different shape and/or there may be a different method of accessing the interior of the club head, such as removing the sole of the club head, the back of the club head, or the like.

Having thus described the present invention by reference to certain of its preferred embodiments, it is noted that the embodiments disclosed are illustrative rather than limiting in nature and that a wide range of variations, modifications, changes, and substitutions are contemplated in the foregoing disclosure and, in some instances, some features of the present invention may be employed without a corresponding use of the other features. Many such variations and modifications may be considered obvious and desirable by those skilled in the art based upon a review of the foregoing description of preferred embodiments. Accordingly, it is appropriate that the appended claims be construed broadly and in a manner consistent with the scope of the invention.

What is claimed is:

1. A golf club head comprising:
a shell comprising a plurality of walls that collectively form a hollow body with a substantially empty or voided cavity, wherein one or more of the walls comprises a striking face configured to strike a golf ball;

a plurality of weights detachably secured to the shell, each of the plurality of weights being located at an accessible location along the shell for shifting a center of gravity of the golf club head;

the shell having an integral step portion extending inwardly from an exterior surface of the shell at an accessible location along the shell, the integral step portion comprising one or more openings into the hollow body of the club head;

a cover secured in the integral step portion, the cover having an interior portion on which one of the plurality of weights is supported;

wherein the accessible location of each of the plurality of weights is selected from a group of locations on the shell, comprising:

a first location near a rear of the club head;
a second location near a toe of the club head; and
a third location near a heel of the club head.

2. The golf club head of claim 1, wherein at least one of the plurality of weights is at least partly threadably secured within the opening in the integral step portion.

3. The golf club head of claim 2, wherein the at least one of the plurality of weights comprises at least in part a threaded

fastener and wherein the threaded fastener is at least partly threadably secured through at least one of the one or more openings into the hollow body.

4. The golf club head of claim 1, wherein one of the plurality of weights is detachably secured within the integral step portion at least partly by press-fitting against a wall in the integral step portion. 5

5. The golf club head of claim 1, wherein one of the plurality of weights is detachably secured within the integral step portion at least partly by one or more latches. 10

6. The golf club head of claim 1, wherein the integral step portion is configured to receive a plurality of interchangeable weights, the plurality of interchangeable weights shifting the center of gravity of the golf club head. 15

7. The golf club head as described in claim 1, wherein the cover component is a port cover. 15

8. The golf club head as described in claim 1, wherein the cover also has an exterior surface opposite the interior surface. 20

9. The golf club head as described in claim 8, wherein the exterior surface of the cover is flush or recessed with respect to outer surfaces of the shell. 25

10. A golf club head comprising:

a shell comprising a plurality of walls that collectively form a hollow body with a substantially empty or voided cavity, wherein at least one of the walls comprises a striking face configured to strike a golf ball; 25
a plurality of weights detachably secured to the shell, each of the plurality of weights being located at an accessible location along the walls of the shell; wherein the location of each of the plurality of weights is selected from a group of locations on the shell comprising:
a first location near a rear of the club head; and
a second location near the face of the club head; 30

each of the plurality of weights being detachable from, and detachably-secured to, the club head for shifting a center of gravity of the golf club head;

an integral recessed portion extending inwardly from an exterior surface of the shell at one of first and second locations, the integral recessed portion comprising one or more openings into the hollow body of the club head; and

10 an cover assembly secured in the integral recessed portion, the cover assembly having an interior portion on which one of the plurality of weights is supported; the cover assembly including a fastener extending through one of the openings into the hollow body of the club head.

11. The golf club head of claim 10, wherein:
the fastener comprises a threaded fastener; and
threaded fastener is detachably and threadably secured to the opening into the hollow body. 15

12. The golf club head of claim 10, wherein:
the fastener comprises a threaded fastener; and
threaded fastener extends into the substantially voided cavity through at least one fastener opening. 20

13. The golf club head of claim 10, wherein the fastener comprises a portion of a weight. 25

14. The golf club head of claim 10, wherein a weight associated with the integral recessed portion does not extend outwardly beyond outer surfaces of the shell surrounding the integral recessed portion. 30

15. The golf club head as described in claim 10, wherein the cover assembly also has an exterior surface opposite the interior surface. 35

16. The golf club head as described in claim 15, wherein the exterior surface of the cover assembly is flush or recessed with respect to outer surfaces of the shell. 40
